CLAIM

The ornamental design for a fuel tank frame, as shown and described.

DESCRIPTION

FIG. 1 is a perspective view of a fuel tank frame; FIG. 2 is a front view of the fuel tank frame of FIG. 1; FIG. 3 is a back view of the fuel tank frame of FIG. 1; FIG. 4 is a left side view of the fuel tank frame of FIG. 1; FIG. 5 is a right side view of the fuel tank frame of FIG. 1; FIG. 6 is a top view of the fuel tank frame of FIG. 1; and, FIG. 7 is a bottom view of the fuel tank frame of FIG. 1. The broken lines illustrate portions of the fuel tank frame and are also bounds of the claimed design, and form no part of the claimed design.

1 Claim, 5 Drawing Sheets
